UNITED STATES PATENT OFFICE.

WILLIAM WALLACE CARMAN, OF EXETER, NEW HAMPSHIRE.

STEAM-BOILER.

SPECIFICATION forming part of Letters Patent No. 317,503, dated May 12, 1885.

Application filed January 5, 1885. (No model.)

To all whom it may concern:

Be it known that I, WILLIAM WALLACE CARMAN, of Exeter, in the county of Rockingham, of the State of New Hampshire, have 5 invented a new and useful Improvement in Steam Boilers or Generators; and I do hereby declare the same to be described in the following specification, and represented in the accompanying drawing, which is a longitudinal section of a boiler containing my invention, the nature of which is defined by the claim herein-after presented.

In the said drawing, A is what is termed a "steam-drum," it being a hollow cylinder 15 closed at its ends, and having its axis horizontal, or about so. In front of and extending below the said drum is a water tight box or vessel, B, that near its upper end opens into the drum, near the lower part thereof, by a conduit, a. Leading out of the said box or vessel 20 B, and inclined relatively to the steam-drum as represented, is a series of pipes, C, each of which by an elbow, D, opens into one of another series of pipes, E, extending downward 25 and leading into another water-tight box or vessel, F, inclined like the pipes C. A pipe, G, leads out of the lower part of the box F, and thence upward, and opens into the rear end or head of the steam drum on or about on 30 a level with the conduit a. The boiler so constructed is suitably arranged in whole or in part within a heating-chamber, H, above, or provided with a fire-place, I, having a grate, K, and ash-pit L, a smoke-discharge flue, M, leading out of the lower part of such chamber. 35 The upright part of the pipe G, I have outside of the chamber H, as represented, in order that the said part of the pipe may indicate by its temperature the rapidity or degree of circulation of the water through the generator.

When the boiler is in operation, the smoke and heated volatile products of combustion pass from the fire-place into and through the

chamber H and between and around the pipes C and E and the boxes B and F, they at the 45 time being filled with water, which also is to extend within the steam-drum to a level above the conduit a. As the water becomes heated it will circulate from the box F up through the pipes E, elbows D, pipes C, box B, steam-drum A, and from the latter will flow into and down the pipe G, and thence back into the box F, the steam generated from the water remaining within the drum A, from whence it may be drawn for being utilized as occasion 50 55 may require. Each of the boxes B and F extends entirely across the heating-chamber H.

I am aware of and do not claim the steam-boiler described and represented in the United States Patents No. 84,607 and No. 288,178, in 60 each of which, instead of one single box at each of the ends of the series or stack of tubes, there is a series of separate boxes, "headers," or "manifolds," a construction which, on account of its great expansion, comparatively speaking, and the difficulty of keeping free from sedimentary deposits, I avoid by having single boxes to extend entirely across the heating-chamber.

I claim—

The combination of the fire-place I and the smoke-chamber H with the steam-drum arranged in the upper part of and extending upward out of and above such chamber, the two boxes B and F, extending across the said chamber in its upper and lower parts, the pipes a and G, connecting such drum and boxes, and the stacks of pipes C and E, connected by elbows D, and opening into and extended from one to the other of the said boxes and 75 80 within the chamber H, all being substantially as set forth.

WILLIAM WALLACE CARMAN.
